UNITED STATES PATENT OFFICE.

EUGENE VALLENS, OF NEW YORK, N. Y.

CIGAR-BOX.

1,102,704.

Specification of Letters Patent.

Patented July 7, 1914.

Application filed June 21, 1913. Serial No. 775,088.

To all whom it may concern:

Be it known that I, EUGENE VALLENS, a citizen of the United States, residing at New York city, in the county of New York and State of New York, have invented certain new and useful Improvements in Cigar-Boxes, of which the following is a specification.

My invention relates to the packaging of 10 cigars, and has for its primary object the preservation of the aroma, as well as the maintenance of a perfectly sanitary condition of the cigars.

Another object contemplated by my invention is the provision of a cigar box in combination with a plurality of recessed partitions disposed at opposite sides of the box and adapted to support individual layers of fragile containers or tubes which 20 close the cigars, the upper set of partitions resting directly upon the terminals of the containers and in turn supporting the succeeding layer of cigars.

A still further object of my invention is 25 to provide means whereby the partitions will be locked against movement while the box is in closed condition, but may be slid longitudinally to permit the initial purchase of the cigar at either end of the partitions when the box is open.

To the accomplishment of the recited objects and others coördinate therewith, the preferred embodiment of my invention resides in that construction and arrangement 35 of parts hereinafter described, illustrated in the accompanying drawings, and embraced within the scope of the appended claims.

Specifically, my invention involves the employment of a fragile container, preferably 40 glass, in which a cigar is designed to be placed and hermetically sealed by suitable means. In combination with this feature I utilize a box of any convenient dimensions and first place a pair of narrow 45 partitions adjacent the inner longitudinal walls of the box. A number of containers with the cigars arranged therein as described, are then placed in the corresponding recesses of the partitions transversely of 50 the box. A second set of partitions is superposed with respect to the containers and rests directly upon the same, and this set is also filled with the containers so that the 55 terminals of each container in the separate trays are supported by the partitions equidistantly from each other. Upon the top

layer of cigars I arrange a piece of felt or similar material so that when the lid of the box is closed the pressure exerted thereby will be sufficient to retain both layers of 60 cigars against lateral movement so that breakage during transit is positively precluded. Upon the other hand, when the lid is raised, owing particularly to the fact that I purposely form the partitions so that they 65 will terminate short of the ends of the box, the upper partition may be moved bodily and simultaneously by simply grasping a container at one end of the set and forcing it in the proper direction. This sliding 70 movement is facilitated by reason of the fact that the containers are preferably constructed of glass and permit the partitions to slide easily and freely thereon. When the layer of 75 the cigars has been so shifted this will allow one to readily purchase the container at either of the extreme ends of the partitions, according to the direction in which the latter were forced, and having initially removed one of the containers the others may 80 be extracted without the slightest difficulty.

In the drawings: Figure 1 is a perspective view of the cigar box embodying my invention. Fig. 2 is a longitudinal section of the box and the containers. Fig. 3 is a detail 85 transverse sectional view taken upon lines 3--3 of Fig. 2. Fig. 4 is a fragmentary perspective view of one of the partitions. Fig. 5 is a detail perspective view of the container, and Fig. 6 is a similar view of the 90 closure for the container.

In said drawings, the numeral 1 designates a tubular container, preferably made of glass, and permanently closed at one end. A cigar as 2, is adapted to be inserted in 95 the container and the latter closed by means of the cork or other suitable device 3 provided with a pulling string 4. In order to insure a hermetic sealing both the cork and string are treated with paraffin or like substance and then a piece of tin foil as 5 is secured around the cork by means of a band 6. In this state the natural aromatic qualities of the cigar are preserved, and it is also prevented from being repeatedly handled by customers when the box containing the usual number of cigars is proffered to 100 allow a selection.

The box heretofore described in a general way is designed particularly for cigars 110 packed in the manner just described, and as will be found upon inspection of Fig.

1, as designated by the numeral 1, is of conventional type. Resting upon the bottom of the box and contacting with the adjacent inner walls are two partitions 7 provided 5 with a plurality of registering substantially arcuate shaped recesses 8. The proper number of containers 1 are arranged to rest in the recesses as shown in Figs. 1 and 2 of the drawings, and upon the tops of the 10 several containers there is a similar set of partitions 9, also supporting containers. Each recess 8 is preferably lined with felt or other soft material so that the opposite terminals of the containers will be at all 15 times well protected. It will also be noted that each set of partitions 7 and 9 are shorter than the longitudinal extent of the box, the purpose of which will be presently explained. Resting upon the top layer of 20 containers is a piece of felt or like material 10, which when the box is closed is forced by the cover 11 downwardly and in turn pressure is transmitted to all of the containers as well as their partitions so that 25 any lateral movement of the partitions is effectively counteracted.

Ordinarily, when the cigars are first opened the ends of the partitions 7 and 9 will be equidistant from the adjacent end 30 walls of the box, and the cigars lying at the extremities of the partitions being so close to the said walls it would obviously be quite inconvenient to grasp or purchase either of these cigars, but by simply placing a little pressure upon one of the cigars at the end of the upper partition and forcing it toward the opposite end of the box there will be sufficient space afforded to 35 permit one to readily remove the first cigar. 40 This sliding movement is expedited considerably by virtue of the fact that the upper partition rests directly upon the last con-

tainers supported by the lower partitions. It is also evident that having extracted the first cigar the remaining cigars may be 45 easily taken from the box, and the same course followed with respect to the lower-most layer after the upper layer has been emptied.

It should be understood that in its broader 50 aspect the invention comprehends the employment not only of the various means described, but of equivalent means for performing the recited functions. While the arrangement shown is thought at the present time to be preferable, it is desired to 55 reserve the right to effect such modifications and variations thereof as may come fairly within the scope of the appended 60 claims.

What is claimed, is:—

1. A cigar package comprising individual containers for said cigars, an outer box or casing in which said containers are arranged in layers, and racks adapted to receive the 65 containers in each layer, said racks being recessed to support said containers, and hold each container in a definite and constant position in said box.

2. A cigar package comprising individual 70 containers for said cigars, an outer box or casing in which said containers are arranged in layers, and racks to support said containers, and hold each container in a definite 75 and constant position in said box, the rack supporting an upper layer being supported on the containers in the next layer below.

In testimony whereof I hereunto affix my signature in presence of two witnesses.

EUGENE VALLENS.
